US0D1090124S

(12) **United States Design Patent** (10) **Patent No.:** **US D1,090,124 S**
(45) **Date of Patent:** **** Aug. 26, 2025**

(54) **CRAFT STORAGE CART**

(71) Applicant: **Shenzhen Tongzhou Technology Co., Ltd.**, Shenzhen (CN)

(72) Inventor: **Nanyan Zeng, Xiangxi (CN)**

(73) Assignee: **Shenzhen Tongzhou Technology Co., Ltd.**, Shenzhen (CN)

(**) Term: **15 Years**

(21) Appl. No.: **29/894,687**

(22) Filed: **Jun. 13, 2023**

(51) LOC (15) Cl. **06-03**

(52) U.S. Cl.

USPC **D34/19; D6/657**

(58) **Field of Classification Search**

USPC D6/329, 641, 642, 647, 653, 655, 655.1, D6/655.15, 655.18, 655.19, 655.22, 657, D6/663, 664, 666, 671, 671.1, 675, 685, D6/686, 691, 691.4, 691.6, 691.7, 691.9; D34/17, 19, 20, 21

CPC B62B 3/005; B62B 3/00; A47B 67/04; A47B 87/0284; A47B 57/404

(57) **CLAIM**

The ornamental design for a craft storage cart, as shown and described.

DESCRIPTION

FIG. 1 is a front perspective view of a craft storage cart, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the craft storage cart, which form no part of the claimed design.

1 Claim, 8 Drawing Sheets
